ROLLING MILL WITH INCLINED ROLLS

Fritz Kocks, Dusseldorf, Germany

Application August 5, 1933, Serial No. 683,871
In Germany February 2, 1933

3 Claims. (CL 80—13)

My invention relates to rolling mills and more especially to rolling mills fitted with inclined or cross rolls, i. e. with rolls whose axes extend in different planes at an angle to one another. 5 It has particular reference to the means for transmitting power to such mills and it is one of the objects of my invention to provide power transmitting means which allow transmitting onto the cross rolls of the rolling mill the highest possible turning moment in order to obtain the 10 highest possible efficiency in operation.

Hitherto the efficiency of rolling mills with cross rolls was impaired by the fact that the turning moment to be transmitted onto the 15 rolls was limited by the diameter of the coupling pins of the rolls or the pinions or of the coupling spindles connecting the rolls to the pinions.

In order to increase the turning moment transmittable to the rolls, I form the cross rolls with 20 coupling pins on both sides and I provide means whereby driving power is fed to the rolls both from the side where the blank enters and from the side where it leaves the rolls.

This arrangement has proved to be particularly 25 advantageous if applied to rolling mills equipped with more than two cooperating cross rolls whose diameters and coupling pins are relatively small.

In the preferred form of my invention I provide two separate housings, one at either end of 30 the mill and a separate pinion for each roll mounted in each housing, both ends of these pinions being supported in suitable bearings formed in or secured to the housings, and I further provide a separate driving means, such as 35 an electromotor, a steam engine or the like, for the pinions mounted in each housing so that the rolls are positively driven from their front and from their rear ends, the two driving means being not mechanically connected with each other.

40 In the drawing affixed to this specification and forming part thereof a rolling mill with inclined rolls embodying my invention is illustrated diagrammatically by way of example.

In the drawing:

45 Fig. 1 is a side elevation and
Fig. 2 a plan view of the mill, while
Fig. 3 is an end view of one of the housings
accommodating the pinions.

Referring to the drawing, 1 and 2 are the cross rolls mounted in a housing 3, each roll being formed with two coupling pins 4, 5, one at either end. 6, 6 are coupling spindles and 7, 8 are coupling boxes connecting these spindles with the coupling pins of the rolls on the one side and with the axes 9 of the pinions 10 on the other side. These axes and the pinions, of which they form part, are supported in bearings provided in the housings 11 and 12, one of which is shown in end view in Fig. 3. Between the pinions mounted in each housing is located a driving wheel 13 which is coupled with and driven by a separate motor 14. The blank (not shown) enters between the rolls from the left, leaving the rolls on the right 15 hand side of the figures, after having passed over a mandrel indicated at 15.

I wish it to be understood that I do not desire to be limited to the exact details of construction shown and described for obvious modifications 20 will occur to a person skilled in the art.

I claim:

1. In a mill for rolling tubular blanks, a plurality of cross-rolls, means for supporting and means for driving said rolls arranged at both ends 25 thereof, shafts connected with said rolls, gears mounted on said shafts at both ends thereof and gears mounted on said driving means adapted to mesh with and to drive said first gears.

2. In a mill for rolling tubular blanks, a plurality of conical cross-rolls, means for supporting and means for driving said rolls arranged at both ends thereof, shafts connected with said rolls, gears mounted on said shafts at both ends 35 thereof, and driving gears mounted on said driving means intermediate said first gears and adapted to drive said first gears.

3. In a mill for rolling tubular blanks, a plurality of conical cross-rolls mounted on shafts, gears mounted on each end of each shaft, independent 40 driving means arranged at both ends of said cross-rolls, said driving means comprising driving gears mounted intermediate said first mentioned gears and adapted to drive the same, said driving means being adapted to transmit equal 45 amounts of power to each end of each roll.

FRITZ KOCKS.
